ELECTRICAL SWITCH.

1,302,730.

Specification of Letters Patent. Patented May 6, 1919.

Application filed May 8, 1918. Serial No. 233,361.

To all whom it may concern:

Be it known that we, EDWARD J. TOMLINSON, and SAMUEL C. McKEOWN, citizens of the United States, residing at Newark and 5 East Orange, respectively, in the county of Essex and State of New Jersey, have invented certain new and useful Improvements in Electrical Switches, of which the following is a specification.

10 This invention relates to a switch for opening and closing an electrical circuit and is particularly adaptable for use in connection with an ignition system, and as shown and described the switch is specially adapted 15 for the control of a high tension magneto, but it is to be understood that the switch is applicable for use in other electrical circuits.

The object of the invention is to provide 20 a switch that is mechanically strong, positive and efficient in its operation, and relatively cheap to manufacture.

Other and further objects will be apparent 25 after a study of the specification and drawing attached thereto.

In the drawing, Figure 1 is a plan view of the switch with the operating handle and cover removed, the switch member being in one position of operation.

30 Fig. 2 is a view similar to Fig. 1 but with the switch member in another position of operation.

Fig. 3 is a sectional view, on the line 3—3 of Fig. 1 through the base member carrying 35 the switch parts but with the switch parts shown in full.

Fig. 4 is a front view of the cover plate and handle in position and with the screws shown therein for attaching the cover plate 40 to the base member.

Fig. 5 is a rear view of Fig. 2 without the fastening screws.

Referring now to the details, in which like numbers refer to corresponding parts 45 in the various views, 1 is a cup shaped base member having a flange 2 with threaded holes 3 therein. Fastened to the bottom of the cup are contact studs 4 and 5. Stud 4 as shown is insulated from the member 1, 50 but the stud 5 being used in the illustration as a grounding stud is not insulated from the base member. Mounted within the cup-shaped member 1 is a U-shaped member 6 having arms 7 and 8. The bottom arm has 55 a hole through which passes a pivotal means

such as a screw 9, same being fastened to the bottom of the member 1 by a nut 10. After the nut 10 is put on the end of the screw, the screw may be riveted over to prevent the nut from coming off. The 60 upper arm 8 has a hole 11 and a slot 12 extending lengthwise of the arm 8. The cross-bar 13 of the U-shaped member 6 has an eye 14 punched downwardly to receive one end of a spring 15, the other end of which is hooked into an eye 16 punched inwardly from the side wall of the cup-shaped member. Extending from the cross-bar 13 is a tongue 17 adapted to engage the switch 65 blades 18 carried by the contact stud 4. A 70 cover plate 19 is adapted to be fastened to the flange 2 by means of special screw studs 20 and a screw 21. The entire switch is adapted to be mounted by screw holes 28 through the cover 19. Studs 20 besides serving to hold the cover plate to the flange 2 are utilized for stops for the handle 22 which has a stud 23 adapted to project 75 through the cover plate 19 to an extent sufficient to allow it to enter the hole 11 in 80 the upper arm 8 of the U-shaped member 6. Stud 23 carries an ear 24 adapted to enter the slot 12 at the same time that the stud 23 enters the hole 11. A slot 25 is made in the cover plate to allow the ear 24 to pass 85 through and as the stud 23 is turned by means of the handle 22 the ear 24 moves in the notched portion 26 of the hub 27 on the inner part of the plate 19. As soon as the ear 24 passes out of line of the slot 25 it will 90 be seen that the handle 22 cannot be removed from the switch, that is to say, the handle 22 can only be removed from the switch in the "off" position.

In the operation of the switch after the 95 handle has been inserted as above described, the turning of the handle causes the U-shaped member 6 to move say from the position shown in Fig. 2 toward the position shown in Fig. 1. When the U-shaped member has reached the position where the center of the pivotal means is in line with the two eyes 14 and 16, the spring 15 will act directly thereafter to snap the U-shaped member 6 over to the position shown in 100 Fig. 1, carrying the handle with it unless obstructed by the operator.

In the operation of an ignition switch, it is usual to push on either side of the switch handle instead of grasping it and when so 105

operated, that is by a push on the side of the handle, the U-shaped member will function as above described.

In the control of a high tension magneto, the usual practice is to short circuit the circuit breaker by a switch or what is the same thing, to ground the free end of the primary winding which is accomplished by the above described switch by connecting the free end of the primary winding to the stud 4 and connecting the ground to the stud 5, it being understood that the U-shaped member 6 is grounded through its pivotal mounting means to the base member 1. It will be readily observed that the switch may be adapted for use in a battery ignition system or in other electrical circuits and I do not wish to be limited to any particular application.

Having thus described our invention what we claim is:

1. In a device of the character described, the combination of a cup-shaped base member having contact studs fastened thereto, one of said studs having contact blades mounted thereon, a U-shaped member pivotally mounted on said base member and having a projecting tongue adapted to engage with said contact blades, a spring having one end attached to the side wall of the base member and the other end attached to the cross-bar of the U-shaped member and adapted to move the U-shaped member quickly to "on" or "off" position after it has been moved beyond a dead center and to hold it in either position, a cover plate for the base member and a handle having a part adapted to pass through said plate and to engage the U-shaped member to move the same from "on" or "off" position by the dead center position, as described.

2. In a device of the character described, the combination of a cup-shaped member having an eye punched from its side wall and having contact studs fastened to the bottom thereof, one of said studs being insulated from said member and carrying contact blades, a U-shaped member pivotally mounted on the bottom of said cup member and having a projecting tongue adapted to engage said contact blades and an eye punched from its cross-bar adjacent to said tongue, said eye in the cup member being located so as to be in line with the eye on the U-shaped member and its pivot when the U member is substantially half way between said contact studs, a spring connected between said eyes to move the U member to "on" or "off" position and to hold it there after it has been moved by the pivot centerline, a cover for closing the top of the cup member and for mounting the switch, a handle having a part

adapted to pass through the cover for engagement with the U-shaped member for moving the same from "on" or "off" position by the pivotal centerline and means cooperating between the cover and handle to prevent its removal except in "off" position.

3. In a device of the character described, the combination of a cup-shaped member having a flange, a cover plate with means for fastening the same to the said flange, a handle having a part adapted to pass through the cover plate only in one position of the handle, a part of said means for fastening the cover plate to the said flange being used also as stops for the arcuate movement of said handle, a U-shaped switch member rotatably mounted on the bottom of the cup member and adapted to be engaged by that part of the handle extending through the cover plate into the cup member and a spring acting on said U-shaped member to help move and to positively hold it and the handle in either an "off" or "on" position.

4. In a device of the class described, the combination of a cup-shaped member having a cover plate fastened thereto, a U-shaped switch member having a hole in each arm of the U, pivoting means passing through one of said holes for rotatably fastening the said switch member to the base of the cup member, the other of said holes having a slot extending along the arm, a handle having a stud with a projecting ear adapted to pass through said cover plate to an extent such that the stud enters the hole in the upper U arm and the ear engages the said slot whereby movement of the handle moves the U-shaped member into "on" or "off" position.

5. In a device of the class described, the combination of a cup-shaped member having a cover plate fastened thereto, a U-shaped switch member having a hole in each arm of the U, pivoting means passing through one of said holes for rotatably fastening the said switch member to the base of the cup member, the other of said holes having a slot extending along the arm, an eye in the wall of the cup-shaped member, an eye in the cross-bar of the U member and a spring held by said eyes, a handle having a stud with a projecting ear adapted to pass through said cover plate to an extent such that the stud enters the hole in the upper U arm and the ear engages the said slot whereby movement of the handle moves the U-shaped member to a position where the said spring will move the U member the remainder of its distance and hold said U member in said position.

In witness whereof, we affix our signatures.

EDW. J. TOMLINSON.
SAMUEL C. McKEOWN.
